DESIGN FOR A CHILD'S COAT

Benjamin Fischer, New York, N. Y.

Application July 19, 1938, Serial No. 78,580

Term of patent 3½ years

To all whom it may concern:

Be it known that I, Benjamin Fischer, a citizen of the United States and residing in Manhattan, in the city, county, and State of New York, have invented a new, original, and ornamental Design for a Child's Coat, of which the following is a specification, reference being had to the accompanying drawing, forming part thereof, wherein

Fig. 1 is a front view of a child's coat showing my new design.

Fig. 2 is a rear view thereof.

The characteristic feature of my design resides in the stitched tucking inserted at each side of the waistline of the panelled coat shown, in association with the matching tucked inserts across the top of the sleeves.

I claim:

The ornamental design for a child's coat, substantially as shown and described.

BENJAMIN FISCHER.
